UNITED STATES PATENT OFFICE.

CORA H. CARTLEDGE, OF PHILADELPHIA, PENNSYLVANIA.

CONTAINER.

1,387,237.

Specification of Letters Patent.

Patented Aug. 9, 1921.

Application filed August 22, 1919. Serial No. 319,142.

To all whom it may concern:

Be it known that I, CORA H. CARTLEDGE, a citizen of the United States, and a resident of Philadelphia, in the county of Philadelphia and State of Pennsylvania, have invented certain new and useful Improvements in Containers, of which the following is a full, clear, and exact description.

The present invention relates to containers, more particularly adapted for containing and dispensing liquid products, such as salad oils, evaporated milk, syrups, etc.

An object of the invention is to provide for an effective draining of the contents of the container and to prevent waste in dispensing from the container by the flowing of the contents over the outer surface of the container.

In containers as now commonly used, there is a narrow flange at the top surrounding the opening which receives the sealing cap, and in dispensing liquid products therefrom, the flange prevents a complete draining of the contents from the container. As a consequence, a considerable waste ensues, and further, in such containers considerable annoyance and waste is caused in the dispensing operation, for the reason that the contents in passing over the flange flows over the outer surface of the container, which not only causes waste, but is very annoying, making the container a disagreeable article to handle. Such objections are overcome by the dispensing container constituting the subject of the present invention.

The present invention is illustrated in the accompanying drawing, in which—

Figure 1 shows in perspective a dispensing container embodying the invention;

Fig. 2 shows a vertical, sectional view;

Fig. 3 shows a top view illustrating the pouring opening; and

Fig. 4 shows a view similar to Fig. 2, but showing the flange cut to form the pouring opening.

Similar reference characters will be employed to designate corresponding parts.

The container consists of a substantially cylindrical body portion 1 permanently closed at its lower end by a bottom 2 and having at its upper end a flange 3 which receives a removable frictionally held sealing cap 4 which fits in and is fixedly held in a circular opening in the flange 3. As so far described, the container is of usual and or-

dinary construction and is of a form which is now commonly used, being generally made of sheet metal such as tin or other suitable thin sheet material. In such containers much difficulty is experienced in draining the contents and this has resulted in a considerable waste. I provide for the effective draining of the contents by providing the body portion 1 with a vertically extending drainage channel 5, which as shown, is formed by bulging the body portion 1, in the process of manufacturing the body portion by a suitable die and extending the flange 3 at one point as shown at 6 to cover the drainage channel at the top, such drainage channel extending downwardly from the upper edge of the body portion 1 to a point at or near the bottom thereof, the bottom of the container being preferably circular, and providing upon the inner surface of the container a drainage channel or gutter. The upper end of the channel 5 is closed by a portion of the flange 3 projecting in the form of a semi-circular lip 6 outside of the flange of the cap 4.

The projection formed by the channel 5, while sufficient to effectively act as a drainer and dispenser, is not large enough to interfere with the packing of the receptacles in a shipping case; in fact, they may be so placed in a shipping case that the projections will come within the space formed between adjacent containers.

As shown in Figs. 3 and 4, the receptacle is opened to form a dispensing receptacle, by cutting an opening into the projection 6 of the cap 3 over the upper end of the channel 5.

In use, the contents can be dispensed as required and the inner channel will effectively facilitate the draining of the entire contents, thus eliminating waste.

Having thus described my invention, I claim as new, and desire to secure by Letters Patent:

1. A dispensing container, comprising a body portion, a vertically extending draining channel formed in the wall thereof and discharging from the upper edge thereof, a flange permanently secured about the upper edge of the wall and extended to cover the upper end of the channel, a filling opening in said flange and a sealing cap fitted in the flange opening.

2. A dispensing container, comprising a

body portion, a vertically extending draining channel formed in the wall thereof and discharging from the upper edge thereof, said channel extending from a point at or 5 near the bottom of the body portion to the upper edge and gradually enlarged on diverging lines from the bottom to the top,

a flange permanently secured to the upper edge of the body portion and extended to cover the upper end of the channel, a filling 10 opening formed in said flange and a sealing cap fitted to the opening.

CORA H. CARTLEDGE.
